(57) **CLAIM**

The ornamental design for the tool handle, as shown and described.

DESCRIPTION

FIG. 1 is a perspective view of the tool handle showing my new design;

FIG. 2 is one side view thereof;

FIG. 3 is the other side view thereof;

FIG. 4 is a top view thereof;

FIG. 5 is a bottom view thereof;

FIG. 6 is a rear view thereof; and,

FIG. 7 is a front view thereof.

The broken lines shown in the drawings illustrate unclaimed portions of the article and form no part of the claimed design.
